UNITED STATES PATENT OFFICE

JOHN C. O'NEILL, OF HAMBURG, NEW YORK.

SASH-FASTENER.

No. 870,641.

Specification of Letters Patent.

Patented Nov. 12, 1907.

Application filed March 12, 1906. Serial No. 305,534.

To all whom it may concern:

Be it known that I, JOHN C. O'NEILL, a citizen of the United States, residing at Hamburg, in the county of Erie and State of New York, have invented a new and 5 useful Improvement in Sash-Fasteners, of which the following is a specification.

This invention relates to improvements in sash fasteners and more particularly to fasteners for securing removable storm sashes and screens in place in the window frames.

The primary object of the invention is to provide a simple and inexpensive and easily operated device which can be readily applied either outside or inside of the storm sashes and screens and which will hold the 15 same securely in position and will prevent rattling thereof.

A further object of the invention is to make a fastener so simple in construction and in mode of attachment that no fitting or cutting of either the sash or window 20 frame is required in applying the same, and the ordinary unskilled householder can easily apply the device.

The fastener also possesses the advantage that it can be used for fastening either sliding window sashes or screens to securely hold the same at any point to which they 25 may be raised or lowered.

In the accompanying drawings: Figure 1 is an outside elevation of a window frame and a storm sash secured therein by sash fasteners embodying the invention. Fig. 2 is an enlarged perspective view of one of 30 these fasteners and the adjacent parts of the window sash and frame. Fig. 3 is an enlarged horizontal section, partly in plan, of a portion of a window frame and storm sash, showing the fastener secured upon the inner side of the sash. Fig. 4 is an enlarged fragmentary horizontal 35 section, partly in plan, of a window, showing the fastener applied to the upper sliding sash.

Like letters of reference refer to like parts in the several figures.

A represents the frame of a window of usual construction, b the outer casing, c the blind stop, d the jamb, e the parting strip, and f the upper window sash thereof.

G represents a storm window sash fitted, as usual, within the outer casing b and resting against the blind stop c of the window frame and held in position therein 45 by fasteners H forming the subject of this invention. Window screens are commonly secured in the window frame in the same position as the storm sash shown, and it will be understood that while the fastener is illustrated in the drawings in connection with a storm sash 50 it is equally well adapted for securing window screens.

The fastener, which is in the nature of a turn button, has a flat body portion h, through a central hole in which a screw h' or other securing device is driven into the rail of the storm sash to pivotally secure the fastener thereto, and has fastening arms h² and h³ extending therefrom in opposite directions. One arm h² extends

from the body portion h in the plane thereof, while the other arm h³ is bent outwardly or extends at an angle to the said body portion h. These arms h² and h³ have sharp edged projections h⁴ and h⁵ extending laterally 60 therefrom, preferably, though not necessarily, in the same direction from the body portion h. The arm h² also has at its outer end, at the side opposite to the lateral projection h⁴, a driving lug or part h⁶ projecting outwardly or at an angle to the plane of said arm, the purpose of which will be hereafter more fully explained.

The fastener of the form shown can, if preferred, be readily made from a flat sheet metal stamping bent or pressed into shape.

This fastener is intended for use on either the outer 70 or inner sides of storm sashes or screens, as occasion may require. When the sash or screen rail is of less thickness than the outer casing of the window frame, as shown in Figs. 1 and 2, the fastener is secured to the outer side of the sash G and the sharp edged projection 75 of the arm h² of the fastener is driven into the wood of the outer casing b by a blow with a hammer on the driving lug h⁶. To release the fastener it is only necessary to similarly strike the free arm thereof a blow or two to release the holding projection. If the outer 80 casing b is sufficiently thicker than the sash G the offset projection h⁵ of the other fastening arm h³ can be driven into the wood of the casing. The former method, however, has been found preferable to this, as the projection h⁴ of the arm h² will cut into the casing 85 farther from its outer edge and a surer hold is insured.

Where the storm sash or screen equals or exceeds in thickness the outer casing of the frame, the fastener is secured to the inner side of the sash, as shown in Fig. 3, 90 and when so used, the offset projection h⁵ of the arm h³ is driven into the blind stop c of the window frame to hold the storm sash or screen in position by a blow or two on the rear side of said projection. In this application of the device the arm h² and its cutting projection 95 cannot be used to hold the sash or screen in place as, if driven down, this arm and its cutting projection would enter the space between the inside of the sash and the blind stop. This projection h⁵ can be readily driven into the blind stop by a blow with a hammer 100 on the inner edge of the offset arm h³ of the fastener, which projects out from the face of the sash so that it can be easily struck.

As shown in Fig. 1, when the fasteners are placed on the right and left hand sides of a storm sash or screen, 105 the arms of the fasteners on one side of the sash extend in an opposite direction from the corresponding arms of the fasteners on the other side of the sash, that is, in the construction the fastening arms h² at the left of the window extend upwardly, while on the right they extend downwardly and the converse is true of the arms h³. If desired, this could be avoided by constructing

the device in two forms, one having the lateral projections extending to the right of the body and the other to the left. The fastener can also be placed on the 5 sliding window sashes or screens for locking them in any position. Such a construction is shown in Fig. 4 in which *f* represents the upper sliding sash of a window of ordinary construction. The fastener is secured on the inner side of the sash and its offset lateral projection *h*⁵ is driven into the parting strip *e*. If the fastener is placed on the lower sash, the cutting edge is 10 driven into the inside stop of the window frame. By this means the windows can be raised or lowered to any desired point and then securely locked in position 15 against all further movement until the fastener is released.

I claim as my invention:

1. A window fastener comprising a body pivoted to one member of a window, an arm extending from said body substantially in the plane thereof, a sharpened projection

extending from one side of said arm and adapted to be driven into another member of the window, and a driving portion on said arm opposite to said sharpened projection, substantially as set forth.

2. A window fastener comprising a body pivoted to one 25 member of a window, an arm offset from said body, and a sharpened projection extending from one side of said arm and adapted to be driven into another member of the window, said offset arm forming a driving portion for said sharpened projection, substantially as set forth.

3. A window fastener comprising a pivoted body, a 30 sharpened projection extending from said body substantially in the plane thereof, a driving portion extending at an angle to the plane of the body, and a second sharpened projection offset from said body, substantially as set 35 forth.

Witness my hand, this 10th day of March, 1906.

JOHN C. O'NEILL.
